UNITED STATES PATENT OFFICE.

CARL FOGELBERG AND GEORGE W. GRAVES, OF CAMBRIDGEPORT, MASS.,
ASSIGNORS TO GEO. WOODS & CO., OF SAME PLACE.

APPARATUS FOR MARKING NOTE-CYLINDERS FOR MUSICAL INSTRUMENTS.

SPECIFICATION forming part of Letters Patent No. 230,540, dated July 27, 1880.

Application filed March 24, 1880. (No model.)

To all whom it may concern:

Be it known that we, CARL FOGELBERG and GEORGE W. GRAVES, citizens of the United States, residing at Cambridgeport, in the county of Middlesex and State of Massachusetts, have jointly invented certain new and useful Improvements in Apparatus for Marking Note-Cylinders for Musical Instruments; and we do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

Our invention relates to a new and useful apparatus for marking note-cylinders for musical instruments. Such note-cylinders are generally provided with projecting metallic pegs and staples driven into the wood of the cylinders and located on the peripheries thereof at proper intervals, so as to produce the desired tunes on the musical instruments in connection with which they are used.

The manner of carrying out our invention is illustrated in the accompanying drawings, in which—

Figure 1 represents a plan view. Fig. 2 represents a side elevation. Fig. 3 represents a cross-section on the line A B, shown in Fig. 1, and Fig. 4 represents a modification thereof.

Similar letters refer to similar parts wherever they occur on the different parts of the drawings.

a represents a wooden templet note-board, provided on its upper surface with note-projections b b' b' b'', as shown. The note-board a is temporarily attached to the laterally-adjustable plate or carriage c, having a rack, c', on its under side, as shown, and capable of a sliding motion between suitable guides on the frame d by means of the pinion e and crank e', as shown.

f f are anti-frictional rollers, upon which the carriage c is supported, so as to be able to slide it without much friction.

g represents the note-cylinder or blank that is to be marked or indented, and its shaft g' is for this purpose made to rest loosely in bear-

ings on the adjustable bars h h, hinged to the frame d at h' h', as shown.

For the purpose of pressing down the note-cylinder g and holding it against the projections b b' b'' on the templet a we use a pair of levers, i i, hinged at i' i' to the stationary standards k k, the lower ends of which levers are made to bear against the ends of the bearing-bars h h when the note-cylinder g is being marked; but we do not wish to confine ourselves to such precise mechanism, as springs, screws, or other or similar well-known pressure-devices may be used to equal advantage.

In Fig. 4 the rotary templet-cylinder l, with its note-projections m m' m'', is shown as being substituted for the sliding templet note-board a in Fig. 1. In Figs. 1, 2, and 3 another modification is shown as consisting of the pencil or marker n, secured to the end of the lever o, that is hinged at o', and provided with a downward-projecting piece, p, jointed at p' to the rocking lever q, that is hinged at q' to the standard-brace k', and having in its outer end a tooth, r, that is made to rest on the templet a by the action of the spring s, as shown.

t represent staples or projections on the templet a, which, when the latter is moved horizontally, cause the tooth r to rise and fall, and by the connecting mechanism, as above described, the pencil or marker n is also made to rise and fall, so as to produce corresponding note-marks, on the cylinder g when the latter is rotated either by means of a crank or other suitable mechanism.

To mark a cylinder it is therefore only necessary to bring it in contact with the projections on the templet-board a or templet-cylinder l, as described, and by moving them together with equal surface velocity it is easily perceived that the projections on the aforesaid templet or templets produce corresponding marks g' g'' g''' on the note-cylinder g, that serve as guides where to drive and locate the pegs or staples that act as note-projections.

The projections on the templet note-board a are shown as isolated sharp-pointed pegs b b, or in groups consisting of a pair of sharp-pointed pegs, b' b', with a square-headed peg, b'', arranged between them. The former—that is, the pointed pegs b b—serve to make

impressions or marks on the note-cylinder to locate and drive isolated pegs or note-projections, and the latter—that is, the combination of the pegs $b' b' b''$ —serve to make impressions or marks for the location on the note-cylinder of staples of the length of the distance between the sharp pegs $b' b'$.

This our apparatus may be used equally well for making indenture or for printing marks on the note-cylinder. In the latter case it would only be needed to have all the projections on the templet of a flattened upper surface and to color them with suitable ink or color.

After a cylinder has been marked or indented as above described it is removed and the pegs and staples driven by hand, as usual. The operation may be repeated to mark or indent any number of cylinders required.

Having thus fully described the nature, construction, and operation of our invention, we wish to secure by Letters Patent, and claim—

1. The within-described method of marking note-cylinders for musical instruments, the same consisting in indenting or marking a cyl-

inder with the proper indentations or marks 25 at the proper places to receive the note-pins by rotating said cylinder in contact with the note-projections on a moving templet, substantially as described.

2. An apparatus for preparing musical-note 30 cylinders for the note-pins, embodying in its construction a moving templet provided with note-projections, which serve to indent or mark on the revolving note-cylinder the proper places for the note-pins, substantially as described. 35

3. In combination with the note-cylinder g , the marker or pencil n , its lever o , connecting-bar p , and lever q , with its projection r and spring s , and a templet board or cylinder or its equivalent, as and for the purpose described. 40

In testimony whereof we have affixed our signatures in presence of two witnesses.

GEORGE W. GRAVES.
CARL FOGELBERG.
